UNITED STATES PATENT OFFICE.

ELWOOD K. PIERCE, OF SPRINGFIELD, OHIO, ASSIGNOR TO THE CAST STEEL DEVICES COMPANY, OF LIMA, OHIO, A CORPORATION OF OHIO.

BOILER PLUG.

Application filed December 30, 1926. Serial No. 157,931.

This invention relates to removable closures for pressure chambers such as tube still junction boxes, headers, return bends, etc., and has for its principal object to provide 5 a pressure resisting closure that can be readily applied or detached, and to permit ready access to the inside of the chamber.

The invention may best be understood by reference to the accompanying drawing, in 10 which

Figure 1 is a plan view of the device disposed in locking position.

Figure 2 is a sectional view taken on line 2—2 of Figure 1.

15 Figure 3 is a perspective view of the removable locking piece, showing details of the locking lugs thereon.

Figure 4 is an enlarged fragmentary view 20 showing a portion of the retaining flanges with which the locking lugs engage.

Referring now to details of the device illustrated herewith, 10 indicates a pressure chamber casing to which the device is applied with annular opening 11 forming a seat 25 for the closure and a cylindrical wall or ring 12 surrounding the outer side of said seat and preferably formed integral with the casing 10.

The closure device comprises a plug member 30 13 having an annular inwardly inclined face 11^a adapted to engage the seat 11, as shown. This plug member is provided with spaced holes 14, 14 in its upper face, adapted to receive a grinding tool of any approved type for grinding said plug in its valve seat, thereby affording a tight pressure resisting joint for the purpose intended. The plug is maintained in place by means of a set screw 15, having a threaded engagement 35 with a removable locking piece 16 which is detachably connected by means of lugs 17—17 disposed or projected from opposite sides of the locking piece 16, and arranged to fit correspondingly shaped openings 18—18, formed in the orifice of the device within the annular wall or ring 12 and above the valve seat 11.

The arrangement is such that the locking piece 16 may be fitted in the orifice with lugs 17—17 registering with openings 18—18. Then by rotating the locking piece through an angle of 90°, the lugs 17—17 are passed under overhanging flanges 19—19 projecting inwardly from the walls 12—12 50 as shown in Figures 1 and 2, and thus secur-

ing the locking piece against withdrawal. Suitable means for limiting rotating movement of the locking piece herein consists of a stop 20 disposed at one side and near the bottom of one of the locking openings 18, as 60 shown in Figures 1 and 4, the arrangement being such that this stop limits rotation of the locking piece at substantially 90° from the position in which it is inserted in or withdrawn from the orifice. In order to 65 accommodate the stop a recess 21 is formed at a corner of the locking lug 17 in position to permit the locking piece to be dropped in the orifice without interference with the stop 20. This recessed portion 21 is clearly 70 shown in Figure 3.

After the locking lug is in position as shown in Figure 1, the set screw is brought into contact with the pedestal 22 on the top of valve member 13 and by screwing down 75 the set screw 15 the plug 13 may be tightened in its seat, forming a tight joint.

Among the advantages of the device above described is the provision for easy removal or replacement of the plug, and means for 80 regrinding the plug when necessary in order to assure a pressure-tight joint at all times. A further advantage is afforded by providing the locking lugs 17, 17 and their cooperating 85 flanges 19, 19 of maximum width, so as to be rotatable through a full 90° angle, and providing correspondingly broad bearing surfaces, so as to eliminate danger of tipping or accidental displacement of the locking piece. 90

I claim as my invention:

1. In a device of the character set forth an annular casing provided with a pair of oppositely disposed locking flanges and intermediate slot openings all of substantially 95 equal circumferential length, a closure member, a locking piece, a screw threaded through said locking member for engaging said closure member, said locking piece having a pair of oppositely disposed lugs adapted to be inserted in said slot openings and rotatable into interlocking position beneath said locking flanges, and a stop formed integrally with said casing at one side of one of said slot openings limiting rotation of said locking member at substantially 100 a quarter turn from its unlocked position, one of said locking lugs being cut away at a lower corner thereof to accommodate said stop. 105

2. In a device of the character described, a chamber having an opening defined by a frusto-conical plug seat, a plug adapted to fit in said seat to form a pressure-tight joint, 5 an annular casing above said opening provided with a pair of oppositely disposed locking flanges and intermediate slot openings, a locking piece adapted to be inserted in said slot openings and rotatable into 10 interlocking position beneath said locking flanges and a screw threaded through said locking member for engaging the top of said plug but detachable therefrom, and tool-operable means on the top of said plug permitting grinding of said plug in its seat 15 when said locking piece and screw are removed.

Signed at Springfield, Ohio, this 27th day of December, 1926.

ELWOOD K. PIERCE.
